UNITED STATES PATENT OFFICE.

WILLIAM R. STOCKING, OF GLASTONBURY, CONNECTICUT, ASSIGNOR TO
M. S. BENEDICT MANUFACTURING COMPANY, OF EAST SYRACUSE,
NEW YORK, A CORPORATION OF NEW YORK.

DESIGN FOR A HANDLE FOR SPOONS, FORKS, OR SIMILAR ARTICLES.

SPECIFICATION forming part of Design No. 36,498, dated August 18, 1903.

Application filed July 16, 1903. Serial No. 165,877. Term of patent 3½ years.

To all whom it may concern:

Be it known that I, WILLIAM R. STOCKING, a citizen of the United States, and a resident of Glastonbury, in the county of Hartford and State of Connecticut, have invented a new, original, and ornamental Design for a Handle for Spoons, Forks, or Similar Articles, of which the following is a specification, reference being had to the accompanying drawings, forming part thereof, for the special and distinguishing features of the design, and in which—

Figure 1 is a front view of a spoon, show-

ing the handle bearing my design and with a fork represented by dotted lines. Fig. 2 is a view showing the back of the handle, the dotted lines showing the fork of Fig. 1 being omitted.

What I claim as new, and desire to secure by Letters Patent, is—

The ornamental design for a handle for a spoon, fork or similar article as shown.

WILLIAM R. STOCKING.
